APPARATUS AND METHOD FOR CONDITIONING OIL AND GAS WELLS

Bernardus E. Mater, Santa Monica, Calif., assignor to Baker Oil Tools, Inc., Vernon, Calif., a corporation of California

Application December 9, 1947, Serial No. 790,574

14 Claims. (Cl. 166—20)

1

The present invention relates to oil and gas wells, and more particularly to the conditioning of flowing wells to initiate production, in the case of new well completions, or to reinstate or increase production, in the case of wells from which production had been previously obtained.

In the completing of a new well or cleaning out of a flowing well, "killing" of the well is often resorted to in order to prevent the well from coming into production before the necessary surface controls have been installed. Where a liner is placed opposite the producing zone or zones, it is desirable to wash behind the liner as well as inside the liner to clean the face of the productive formation and the well bore, for the purpose of obtaining the flow of well production to the top of the bore hole.

In completing a new well, the well bore is ordinarily full of drilling mud, which must be removed before the well can be placed on production. The liner is run in the well on a tubular string to the desired location, and the outside of the liner then washed with water or oil until clear returns are obtained. Where formation pressures are high, the well may come into production during this operation, necessitating refilling of the well bore with drilling mud to offset the pressure, which is referred to as "killing" the well. Special devices can then be installed at the surface to permit a re-washing operation to take place and placing of the well in production with the high formation pressure under effective control. For that matter, such devices may also be installed originally to control the well.

Regardless of their time of installation, these special devices form a permanent part of the well apparatus, representing a costly investment in equipment.

Although the special, permanently installed equipment is effective in enabling a new well to be completed under high pressure conditions, it cannot thereafter be used to recondition, or clean out the well after the latter has been placed in production. As a result, the well must be killed by pumping in drilling mud or water, to permit removal of the special equipment and its modification or re-adaptation to the cleaning out process. Since most wells require cleaning out one or more times during their flowing life, it is readily apparent that repeated killing may be required, with the attendant hazard of sealing off the producing zones and plugging of the liner or casing perforations, which permanently affects the well production. In addition, the cost involved is very substantial.

2

Accordingly, it is an object of the present invention to overcome the aforesaid disadvantages by enabling proper completion of a well, and its subsequent cleaning out or reconditioning, to take place without the necessity for killing the well.

A further object of the invention is to complete a well through use of equipment which can also be utilized for subsequent cleaning out operations without requiring the well to be killed.

Another object of the invention is to decrease the amount of equipment remaining in a flowing well after its completion and placement on production.

15 Still another object of the invention is to provide a well installation capable of use in both completing and reconditioning a flowing well without killing the well, and which may be retrieved for use in another well, if desired.

20 This invention has other objects which will become apparent from a consideration of the following description and the apparatus shown in the drawings accompanying and forming part of the present specification. This apparatus and method will now be described in detail to illustrate the general principles of the invention, but it is to be understood that such detailed description is not to be taken in a limited sense, since the scope of the invention is best defined by the claims appended hereto.

25 Referring to the drawings:

Figures 1a and 1b together form a longitudinal elevational and sectional view of an apparatus in a well bore, with the parts in one operative position, Fig. 1b representing a lower continuation of Fig. 1a;

30 Fig. 2 is a view similar to Fig. 1b, disclosing certain parts in another operative position;

35 Figs. 3a, 3b and 3c together form a longitudinal elevational and sectional view of the well bore, with the parts in still another operative position, Fig. 3b forming a lower continuation of Fig. 3a and Fig. 3c forming a lower continuation of Fig. 3b;

40 Fig. 4 is an enlarged longitudinal section taken along the line 4—4 on Fig. 3b;

Fig. 5 is a cross-section taken along the line 5—5 on Fig. 4; and

45 Fig. 6 is an enlarged longitudinal section taken along the line 6—6 on Fig. 3a.

50 As disclosed in the drawings, a string of casing 10 is positioned in a well bore. This casing may be encased in a suitable cementitious seal 11 terminating at the lower end or shoe 12 of the casing string. The well bore is drilled below the

shoe through one or more productive zones 13, from which flowing well production is to be obtained.

In order to prevent possible sloughing in or sanding of the bore well, it is desired to place a liner 14 opposite the producing formation 13. This liner may be of any suitable type, such as a wire-wrapped, slotted, perforated, or gravel packed liner portion 14a coupled to the desired length of blank pipe 14b. Usually, the lower end of the liner has a set shoe 15 threadedly or otherwise secured to it, there being a liner hanger 16 attached, in a known manner, to its upper end. The liner hanger, as is well known, serves to support the liner 14 from the casing string 10, with the perforated portion 14a of the liner disposed at the required location opposite the producing formation 13.

The liner hanger 16 may be of any suitable type, such as the specific tool disclosed in the patent to E. Burns, 2,310,572, patented February 9, 1943, for "By-pass Type Liner Hanger." As shown somewhat diagrammatically in the drawings, the tool includes slips 17 for anchoring the liner hanger and the depending liner to the well casing 10, and also packing rings 18 for outward expansion into sealing engagement with the wall of the casing. The liner hanger further includes a liner setting tool 19, which forms an essential part of a tubular string 20, of drill pipe or tubing, running to the top of the well bore. The tubing string also includes a portion depending from the setting tool 19 and running through the liner 14 for threaded engagement with the set shoe 15. This threaded connection preferably, and usually, consists of left hand mating male and female threads 21.

The set shoe 15 includes an upwardly closing and downwardly opening poppet valve 22, whose conical head moves upwardly into engagement with a companion seat 23 in the body 24 of the shoe. Such engagement occurs under the influence of a helical spring 25 surrounding the valve stem 26 and bearing against the head 22 and also against a spider portion 27 of the shoe body. When the lower end of the tubing string 20 is threaded in the shoe 15, fluid pumped down the tubing string opens the valve 22 and passes down around the spider 27 for discharge through a plurality of ports or passages 28 in the shoe, thence flowing upwardly through the annulus 29 around the liner 14.

In order to facilitate unthreading or disconnection of the lower end of the tubing string 20 from the set shoe 15, an expansion joint 30 is mounted in the tubing string, preferably immediately above the shoe. This expansion joint (see Fig. 4) includes an inner mandrel 31 connected to a sub 32, which can be threaded into the shoe. The mandrel is telescoped within an outer barrel 33 connected to a collar 34 coupled to an adjacent section of tubing. The mandrel and barrel are slidable with respect to each other, leakage between the interior and exterior of the tubing string being prevented by suitable side seals 35 on a mandrel head 36 engaging the inner wall of the barrel 33.

In addition to the telescopic relationship between the mandrel and barrel, rotation of the barrel 33 is transferable to the mandrel through one or more internal splines 37 formed on the lower portion 33a of the barrel, which are engageable with companion external extended splines or keys 38 on the mandrel. It is apparent that rotation of the barrel 33 for the pur-

pose of unthreading the sub 32 from the set shoe 15 is transmitted to the mandrel 31 by virtue of the driving connection that can be effected between the splines, 37, 38.

6 The upper end of the casing string 10 is constituted by a tubing head 39, from which one or more flow lines 40 may extend (see Figs. 1a and 3a). Flow through these lines is controlled by suitable manually operable valves 41. For a 10 purpose to be explained hereinafter, an auxiliary casing 42, which can be of comparatively short length (20 feet to 40 feet, for example), is mounted within the upper end of the casing, being supported by the tubing head 39 in any suitable manner, as by attaching its upper end to a tapered ring 43 fitting within a companion downwardly and inwardly tapered portion 39a of the tubing head. The lower end 42a of the auxiliary casing is preferably beveled or flared outwardly, 20 there being a plurality of ports or circular holes 44 disposed in the auxiliary casing at a convenient point above its beveled end.

The apparatus disclosed in the drawings further includes a tubing hanger 45, which forms 25 a component part of the tubing string 20, being connected therein at a predetermined point along its length. The upper end of the tubing hanger has a nipple 46 secured to it, whose terminal is provided with a left hand thread 47 adapted to 30 be received within a mating left hand thread of a collar 48 secured to the portion 20a of the tubing string 20 thereabove.

The upper portion 20a of the tubing string extends through a master gate valve 49 secured to 35 the tubing head 39 in any suitable manner, as through use of screws or studs 50 passing through their opposed flanges 51, 52. The upper portion extends also through a pressure control unit or 40 blowout preventer 53 suitably secured to the upper portion of the gate valve 49. This blowout preventer may be of any desired type, such as that described in the patent to F. M. Kilmer, Jr., 1,930,361, patented October 10, 1933, for "Contractile and Expansible Well Packer." It includes a rubber packing element 54, which is subjected to external pressure to cause it to close inwardly upon the tubing string 20a. Fluid under 45 pressure necessary for the actuation of the pressure control unit 53 can be supplied through a suitable inlet pipe 55 threaded into the body of the unit.

The upper portion of the tubing string 20 further includes a tubing float collar 56, to prevent 50 upward passage of fluids through the tubing string. This float collar may assume various forms. As particularly shown in Fig. 6, it consists of an outer collar 57 whose ends are threaded to adjacent tubing sections 58, 59 to hold them in spaced relation, there being a valve seat 60 threaded in this collar portion. A valve head 61 is movable upwardly into engagement with the tapered surface of the seat to close the valve against upward flow fluids under the influence of 55 pressure in the tubing string below the float collar 56. The valve head is also moved upwardly by a helical spring 62 surrounding a valve stem 63. The spring engages a guide 64 extending upwardly from the seat 60, and one or more nuts 65 threaded on the stem. Fluids under pressure can be pumped down the tubing string 20 through 60 the float collar 56, passing through side apertures 66 in the extension 64 and around the valve stem 63, unseating the head 61 and passing down through the tubing string below the tapered 65 seat 60.

The tubing hanger 45 includes a suitable packing 67, such as a packing sleeve, which inherently tends to assume a retracted position, but which can be foreshortened and expanded radially into engagement with the inner wall of the auxiliary casing 42, with which it is designed to cooperate. The tubing anchor further includes an expander 68 below its packing, having downward and inwardly inclined surfaces 68a cooperable with companion surfaces on a plurality of slips 69 adapted to be expanded outwardly into anchoring engagement with the auxiliary casing, to support the entire length of the tubing string depending from the tubing anchor 45.

Any suitable type of tubing hanger 45 can be employed, so long as its slips 69 can be expanded outwardly into anchoring engagement with the auxiliary casing 42 to support the length of tubing below the hanger, and which can also be retracted from engagement with the casing and locked in retracted position whenever it is desired to move the tubing string in a downward direction. In addition, the tubing anchor should include preferably the retractable packing 67. One form of packer which can serve as a tubing hanger is described in the patent to R. C. Baker, 2,368,400, granted January 30, 1945, for "Releasable Well Packer," which can be inverted from the position shown in the patent to the one disclosed in the present drawings. Since the specific structure of the tubing hanger forms no part of the present invention, further details need not be given in the specification since they may be found in the Baker patent referred to above.

Following completion of the drilling operation to form the lower portion of the well bore below the outer casing string 10, which runs through the productive zone 13, the drill pipe and drill bit are pulled and the liner is arranged for running in the well bore. The set shoe 15 is threaded on the lower end of the liner 14, which is attached to the upper end of the liner hanger 16. The tubing string 20, with the liner hanger setting tool 19 and expansion joint 30 incorporated therein, is then extended through the liner 14 and the left hand sub 32 threaded into the set shoe. This combination is run through the well casing 10 by means of the tubing string 20 and the liner hanger slips 17 set temporarily in the well casing at a convenient point below the depth at which the lower end of the auxiliary casing 42 is to extend. This auxiliary casing may then be placed over the tubing string 20 and run in the casing 10 until its supporting head 43 is received within the casing head 39. Suitable side seals 43a may be provided on the supporting head for engagement with the tubing head 39, in order to prevent leakage therebetween.

The liner hanger slips 17 are then retracted and lowering of the liner 14 continued. The tubing hanger 45 is incorporated in the tubing string at a predetermined location, with its left hand threaded nipple 46 secured to the companion threaded collar 48 on the adjacent tubing section thereabove. Of course, the tubing hanger parts 67, 69 are in retracted position, to allow the entire tubing string to be lowered through the well casing and the well bore until the liner 14 has been placed in the desired location opposite the producing horizon 13. The tubing float collar 56 and a relief valve 71 are incorporated in the tubing string above the left hand threaded connection 47, 48, being preferably placed at such locations as to be disposed above the surface equipment 49, 53 when the tubing hanger 45 is anchored in

packed-off condition within the auxiliary casing 42.

If desired, the tubing hanger 45 may be set temporarily in the auxiliary casing 42 to support the tubing string therebelow and the liner 14 attached to it while the master gate valve 49 and pressure control unit 53 are installed. Thereafter, the remaining upper portion 20a, 61, 56 of the tubing string can be inserted through the last two-mentioned units 49, 53, and the collar 48 threaded on to the companion nipple 47. The tubing anchor 45 can then be released to place its packing 67 and slips 69 in retracted positions, these elements being locked in their retracted positions. The entire tubing string 20 may now be lowered to place the liner 14 at its desired location in the well bore opposite the producing zones 13. When in such location, the tubing hanger 45 is disposed below the auxiliary casing 42 and well within the main casing string 10.

When the liner landing depth has been reached, the tubing string 20 is manipulated to set the liner hanger slips 17 in the main casing 10, thereby supporting the liner 14 from the casing string (see Figs. 1a and 1b). At this time, however, the liner packing 18 remains in retracted position. Washing fluid, such as water or oil, can now be pumped down the tubing string 20, passing outwardly through the ports and passages 28 in the set shoe 15 for upward flowing along the exterior of the liner 14 and along the face of the formation 13. This washing fluid passes upwardly through the annulus between the liner 14 and casing string 10 and the annulus around tubing string 20, proceeding through this latter annulus and through the space between the main casing string 10 and auxiliary casing 42 for outward passage through the pipes 40 connected to the tubing head 39.

During this washing operation the pressure control unit 53 is closed, to ensure passage of the returns out through the lines 40 to the mud pit for disposal. The washing operation is continued, in the manner described, until clear returns are obtained at the surface, or until the well starts producing for a sufficiently long period to remove all mud from the formation wall and the annulus around the liner 14.

During the aforementioned washing operation, the liner hanger packing 18 is retracted, to direct upward flow of the substances through the annulus around the liner 14. After the washing operation on the outside of the liner has been completed, the liner hanger 16 is packed off by expanding its packing 18 against the casing 10, in a known manner. The entire tubular string 20 is then rotated to unscrew the sub 32 from the set shoe 15, the tubing string then being elevated slightly to position the sub slightly above the set shoe (see Fig. 2). Washing fluid may then be pumped down the tubing string 20, passing out of its lower end and flowing upwardly around the tubing string through the inside of the liner 14, since outward flowing around the exterior of the liner is essentially prevented by the expanded packing 18 of the liner hanger. The washing operation is continued until clear returns are observed at the surface of the well bore. The washing fluid flows through the annulus between the tubing string and liner, and thence upwardly through the annulus between the casing string 10 and tubing string 20, flowing outwardly through the lines 40 to the mud sump, in the same manner as the fluid employed in washing the outside 70 75 of the liner.

The tubing string is next elevated to locate the tubing hanger 45 inside the auxiliary casing 42, as disclosed in Fig. 3a, the excess tubing in the string above the pressure control unit 53 being removed as the tubing is pulled from the well bore. The tubing string is manipulated to set the tubing hanger slips 69 and packing 67 against the auxiliary casing 42, in order to support the weight of the depending tubing below the hanger 45.

During the washing operations described above, the relief valve 71 and the tubing float collar 56 would ordinarily be disposed at some point within the casing 10. These two members are preferably connected in the tubing string 20 a sufficient distance above the tubing hanger 45 to insure their location a convenient distance above the pressure control unit 53 after the tubing hanger has been set in packed-off condition within the auxiliary casing 42. A line 72 with a control valve 73 therein, can then be connected to the relief valve, the line running to the pit or sump. After the tubing hanger 45 has been anchored to the auxiliary casing 42, the relief valve is opened by opening the valve 73, and the well allowed to flow through the tubing 20 to relieve its internal pressure. If desired, the lines 40 connected to the tubing head 39 can be closed when the relief valve 71 is open, or these lines 40 may also remain open, in order to substantially equalize the pressure internally and externally of the tubing string.

The tubing string 20a above the surface connections 49, 53 is then rotated to the right to unscrew the landing nipple collar 48 from the fishing nipple 46 (see Fig. 3a). The upper portion 20a of the tubing string is then elevated until the landing nipple collar 48 is disposed immediately above the master gate valve 49 and immediately below the pressure control unit 53. The master gate valve 49 can then be closed, to permit the tubing string portion 20a thereabove to be removed completely through and from the pressure control unit 53. The latter can then also be removed and the usual surface controls installed for producing the well.

During all of the operations described above, the well is under control. In the event that the displacement of the drilling mud and the washing of the formation cause the well to start producing, such productive flow cannot pass upwardly through the tubing string because of the upward closing of the valve 61 in the tubing float collar 56. The only flow path for the well production and washing fluid is through the annulus between the casing string 10 and liner 14, and between the casing string and tubing string 20, from where the flow proceeds through the lines 40 connected to the tubing head. If the flow rate is too high, these latter lines may be closed completely by their valves 41, or partially throttled.

During the elevation of the tubing string 20 to place the tubing hanger 45 within the auxiliary casing 42, the well is still under full control since the pressure control unit 53 can be readily packed off around the tubing string by introducing fluid under pressure through the line 55. At the same time, the tubing float collar 56 prevents upward flow of fluids, and the valve or valves 41 controlling the tubing head lines 40 can be suitably manipulated to maintain appropriate well control.

During unscrewing of the landing collar 48 from the adjacent nipple 46 connected to the tubing hanger 45, the well is still under control, which is also true of the removal of such discon-

nected upper tubing sections 20a from the well casing to a point above the master gate valve 49, which is then closed, as described above, to completely shut off the well flow upwardly through the auxiliary casing 42. Of course, the subsequent connection of the surface controls permits the well to be produced in the desired manner.

The tubing hanger 45 is located in the tubing string 20 at such point as to ensure the placing of the lowermost end of the tubing string at the desired depth in the well casing 10, at which it is intended for the well production to enter the tubing string during normal operation of the well. This point will ordinarily be above the perforated liner 14, although its best location must be determined to suit each well condition. As indicated above, the relief valve 71 and tubing float collar 56 are also connected in the tubing string at a point above the tubing hanger 45 which places them at a convenient operating location above the pressure control unit when the tubing hanger 45 is set in the auxiliary casing 42.

In the method of completing an oil well described above, the tubing hanger 45, liner setting tool 19 and expansion joint 30 are left in the producing string 20. Because of the characteristics of these items of equipment, they can be employed subsequently in cleaning out operations, to bring the flowing well back into production, or to increase its declined production due to sanding or partial sanding of the well. Such cleaning out operations can take place without the necessity of killing the well.

In performing a cleaning out operation, the master gate valve 49 is closed and the pressure control unit 53 is installed in place. The upper portion 20a of the tubing string heretofore used, including the landing nipple collar 48, relief valve 61 and tubing float collar 56, is then inserted in position above the pressure control unit, the landing nipple being moved through pressure control unit 53 to a point above the movable element of the gate valve 49. The pressure control unit is actuated to produce engagement of its packing element 54 with the exterior of the tubing string. The gate valve 49 is then opened to allow entry of the tubing string portion 20a into the auxiliary casing 42 to a point adjacent the nipple 46. The tubing string is then rotated to the left to thread the landing nipple collar 48 on to the nipple 46 extending from the tubing hanger 45.

The tubing string 20a is then manipulated to 55 retract the tubing hanger packing 67 and slips 69, and to lock them in retracted positions, as fully described in the Baker patent above referred to. The entire tubing string 20, including all portions below the tubing hanger 45, can then be lowered through the well casing 10 and liner 14 to the point where the sand can be washed out from the inside of the liner by pumping washing fluid down to the tubing string. If necessary, the left hand sub 32 at the lower end 60 of the expansion joint 30 can be re-threaded into the set shoe 15 to enable washing fluid to pass behind the liner 14, cleaning the face of the formation 13, and ensuring its full production once again.

After the washing operation has been completed, the tubing string 20 can be elevated, the tubing hanger 45 again set in the auxiliary casing 42, the portion 20a of the tubing string including the tubing float collar 56 and relief valve 71 again removed through the pressure control

unit 53, the master gate valve 49 closed, the pressure control unit 53 removed, and the surface connections re-installed.

In view of the retrievability of the tubing hanger 45 through retraction of its slips 69 and packing 67, the tubing hanger 45, liner setting tool 19, expansion joint 30, and all of the other tubing sections depending from the tubing hanger 45, can be removed from the well bore whenever desired, as when after the well has ceased flowing. They can then be installed in another well, thus allowing the equipment to be used for its full operating life.

It is to be noted that new wells can be completed and placed on production without killing the well whenever the tubing string is to be removed from the well bore. Complete control of the well is maintained during its entire conditioning, avoidance of pumping drilling mud into the well bore to "kill" the well preventing possible diminution of subsequent well flow through mudding off of the producing zones and plugging of the liner perforations. The time for completely washing out the well and placing it on production is reduced considerably, and the quantity of equipment remaining in the well is also substantially less than heretofore required.

After the well has been on production, it can be reconditioned without killing the well with mud or water. Washing operations can take place with oil and the equipment within the well casing can be readily used in the reconditioning operation, during which the well is under complete control at all times.

The inventor claims:

1. The method of conditioning a well bore: which includes connecting the lower portion of a liner to a tubular string and lowering said liner on said tubular string through casing in said well bore; hanging said liner from said casing without packing off the space between said liner and casing; while said liner is hanging from said casing pumping washing fluid down said tubular string and around said liner; then packing the space between said liner and casing string while said liner is hanging from said casing string; then disconnecting said tubular string from said liner; pumping washing fluid down said tubular string for upward flow within said liner; then hanging said tubular string in said casing; disconnecting the upper portion of said tubular string above its hanging location in said casing; and withdrawing said upper portion from said casing.

2. The method of conditioning a well bore: which includes providing a casing string in said well bore, a valve at the upper end of said string, and a pressure control unit above said valve; connecting the lower portion of a liner to a tubular string and lowering said liner on said tubular string, the tubular string extending through said valve and unit; hanging said liner from said casing while said liner remains connected to said tubular string without packing off the space between said liner and casing; while said liner is hanging from said casing pumping washing fluid down said tubular string for upward flow around said liner; then packing the space between said liner and casing string while said liner is hanging from said casing string; then disconnecting said tubular string from said liner; pumping washing fluid down said tubular string for upward flow within said liner; then hanging said tubular string in said casing string; disconnecting the upper portion of said tubular string above its hanging location in said casing string; withdraw-

ing said upper portion from said casing string to locate the lower end of said disconnected upper portion between said valve and unit; and closing said valve.

3. The method of conditioning a well bore: which includes providing a casing string in said bore, a valve at the upper end of said string, and a pressure control unit above said valve; connecting the lower portion of a liner to a tubular string and lowering said liner through said casing string on said tubular string, said tubular string extending through said valve and unit; closing said tubular string against upward flow of fluid therethrough; hanging said liner from said casing string while said liner remains connected to said tubular string without packing off the space between said liner and casing; while said liner is hanging from said casing string pumping washing fluid down said tubular string for upward flow around said liner; then packing the space between said liner and casing string while said liner is hanging from said casing string; then disconnecting said tubular string from said liner; pumping washing fluid down said tubular string for upward flow within said liner; then hanging said tubular string in said casing string; disconnecting the upper portion of said tubular string above its hanging location in said casing string; withdrawing said upper portion from said casing string to locate the upper end of said disconnected upper portion between said valve and unit; and closing said valve.

4. Apparatus for conditioning wells: which includes a liner; a tubular string extending through said liner and attached to the lower portion of said liner, said tubular string having a retrievable tubing hanger incorporated therein and disposed above said liner in spaced relation thereto; a casing to which said hanger can be anchored; said hanger having an expandable and retractable packing embodied therein movable laterally into and out of engagement with the casing for sealing said hanger within said casing and preventing fluid flow along the exterior of the hanger; a valve through which said string extends; and a pressure control unit above said valve through which said string extends.

5. Apparatus for conditioning wells: which includes a main casing string; an auxiliary casing string depending within said main casing string to a substantial extent from the upper end of said main casing string; a main valve connected to the upper end of said main casing string; a pressure control unit above said valve; a liner adapted to be lowered through said main casing string; a tubular string connected to said liner and extending through said valve and unit, said tubular string having a retrievable tubing hanger incorporated therein for anchoring in said auxiliary casing string, said hanger including expandable and retractable slip means engageable with said auxiliary casing string and also an expandable and retractable packing engageable with said auxiliary casing string.

6. Apparatus for conditioning wells: which includes a main casing string; an auxiliary casing string depending within said main casing string to a substantial extent from the upper end of said main casing string; a main valve connected to the upper end of said main casing string; a pressure control unit above said valve; a liner adapted to be lowered through said main casing string; a tubular string connected to said liner and extending through said valve and unit, said tubular string having a retrievable tubing hanger

incorporated therein for anchoring in said auxiliary casing string against downward movement, said tubing hanger having an expansible and retractable packing for sealing engagement with said auxiliary casing string, and a check valve in said tubular string above said hanger.

7. In apparatus for conditioning wells: a liner hanger secured to said liner and having slips and packing means for engagement with a well casing; a tubular string having a retrievable tubing hanger incorporated therein above said liner hanger and a setting tool connected to said liner hanger; said retrievable tubing hanger including expansible and retractable slip means and expansible and retractable packing means movable laterally into and out of engagement with the well casing; and a valve in said tubular string above said hanger.

8. Apparatus for conditioning wells: which includes a main casing string; an auxiliary casing string depending within said main casing string to a substantial extent from the upper end of said main casing string; a main valve connected to the upper end of said main casing string; a pressure control unit above said valve; a liner adapted to be positioned below said main casing string, said liner having a set shoe on its lower end; a tubular string connected to said set shoe and extending through said main valve and unit; a liner hanger secured to the upper end of said liner, said liner hanger having slips and packing means both engageable with said main casing; a retrievable tubing hanger incorporated in said tubular string for anchoring in said auxiliary casing string; said retrievable tubing hanger including expansible and retractable slip means engageable with said auxiliary casing string and expansible and retractable packing means engageable with said auxiliary casing string; a setting tool incorporated in said tubular string for connection with said liner hanger; and a downwardly opening check valve in said tubular string above said tubing hanger.

9. Apparatus for conditioning wells: which includes a main casing string; an auxiliary casing string within and at the upper end of said main casing string; a main valve connected to the upper end of said main casing string; a pressure control unit above said valve; a liner adapted to be lowered through said main casing string; a tubular string connected to said liner and extending through said valve and unit, said tubular string having a retrievable tubing hanger incorporated therein for anchoring in said auxiliary casing string; a fluid flow line communicating with the annulus between said main and auxiliary casing strings; said auxiliary casing string extending substantially below said fluid flow line; and means providing a seal above said fluid flow line between said main and auxiliary casing strings.

10. Apparatus for conditioning wells: which includes a main casing string; an auxiliary casing string within and at the upper end of said main casing string; a main valve connected to the upper end of said main casing string; a pressure control unit above and communicable with said valve; a liner adapted to be lowered through said main casing string; a tubular string connected to said liner and extending through said valve and unit, said tubular string having a retrievable tubing hanger incorporated therein for anchoring in said auxiliary casing string, said hanger having an expansible and retractable packing for sealing with said auxiliary casing string; and

a fluid flow line communicating with the annulus between said main and auxiliary casing strings; said auxiliary casing string extending substantially below said fluid flow line; and means providing a seal above said fluid flow line between said main and auxiliary casing strings.

11. Apparatus for conditioning wells: which includes a main casing string; an auxiliary casing string within and at the upper end of said main casing string; a main valve connected to the upper end of said main casing string; a pressure control unit above and communicable with said valve; a liner adapted to be lowered through said main casing string; a tubular string connected to said liner and extended through said valve and unit, said tubular string having a retrievable tubing hanger incorporated therein for anchoring in said auxiliary casing string, and also a check valve in said tubular string above said hanger, said hanger having an expansible and retractable packing for sealing with said auxiliary casing string; and a fluid flow line communicating with the annulus between said main and auxiliary casing strings; said auxiliary casing string extending substantially below said fluid flow line; and means providing a seal above said fluid flow line between said main and auxiliary casing strings.

12. Apparatus for conditioning wells: which includes a main casing string; an auxiliary casing string within and at the upper end of said main casing string; a main valve connected to the upper end of said main casing string; a pressure control unit above said valve; a liner adapted to be lowered through said main casing string; a tubular string connected to said liner and extending through said valve and unit, said tubular string having a retrievable tubing hanger incorporated therein for anchoring in said auxiliary casing string against downward movement, said tubing hanger having an expansible and retractable packing for sealing engagement with said auxiliary casing string, a check valve in said tubular string above said hanger; and a fluid flow line communicating with the annulus between said main and auxiliary casing strings; said auxiliary casing string extending substantially below said fluid flow line; and means providing a seal above said fluid flow line between said main and auxiliary casing strings.

13. Apparatus for conditioning wells: which includes a main casing string; an auxiliary casing string within and at the upper end of said main casing string; a main valve connected to the upper end of said main casing string; a pressure control unit above and communicable with said valve; a liner adapted to be lowered through said main casing string; a liner hanger secured to said liner for supporting said liner from said main casing string; a tubular string connected to said liner and extending through said valve and unit, said tubular string having a retrievable tubing hanger incorporated therein for anchoring in said auxiliary casing string against downward movement, said tubing hanger having an expansible and retractable packing for sealing engagement with said auxiliary casing string, a check valve in said tubular string above said hanger; and a fluid flow line communicating with the annulus between said main and auxiliary casing strings; said auxiliary casing string extending substantially below said fluid flow line; and means providing a seal above said fluid flow

13

line between said main and auxiliary casing strings.

14. Apparatus for conditioning wells: which includes a main casing string; an auxiliary casing string within and at the upper end of said main casing string; a main valve connected to the upper end of said main casing string; a pressure control unit above said valve; a liner adapted to be positioned below said main casing string, said liner having a set shoe on its lower end; a tubular string connected to said set shoe and extending through said main valve and unit; a liner hanger secured to the upper end of said liner, said liner hanger having slips and packing means both engageable with said main casing; a retrievable tubing hanger incorporated in said tubular string for anchoring in said auxiliary casing string; a setting tool incorporated in said tubular string for connection with said liner hanger; a downwardly opening check valve in said tubular string above said tubing hanger; and a fluid flow line communicating with the annulus

14

between said main and auxiliary casing strings; said auxiliary casing string extending substantially below said fluid flow line; and means providing a seal above said fluid flow line between said main and auxiliary casing strings.
